UNITED STATES PATENT OFFICE.

CHARLES G. RUSH, OF CHICAGO, ILLINOIS.

ADJUSTABLE COMBINED SHADE AND HOOD HOLDER.

1,083,218.

Specification of Letters Patent.

Patented Dec. 30, 1913.

Application filed March 28, 1913. Serial No. 757,309.

To all whom it may concern:

Be it known that I, CHARLES G. RUSH, a citizen of the United States, residing at Chicago, in the county of Cook and State 5 of Illinois, have invented a certain new and useful Improvement in Adjustable Combined Shade and Hood Holders, of which the following is a specification.

This invention relates to electric light fixtures, and particularly to such fixtures in which one or more lamps are mounted on the face of a fixture, hood, canopy or receptacle secured to the ceiling or side wall for concealing the socket and the wiring 15 connections to the lamp.

The invention is especially applicable to apparatus of this class in which the protecting fixture hood is of porcelain, thin brass or other more or less fragile material.

20 The special object of this invention is to provide practically concealed means for mounting the fixture hood and the shade holder with its glassware upon a single wall or ceiling support, like a gas pipe end, projecting therefrom, in such a way that the hood is itself supported at a plurality of points thereby reducing the liability of breakage and that the device is adjustable to, within limits, accommodate hoods of different heights and to allow movement of the hood for making wiring connections.

35 The invention consists in a device for carrying out the foregoing object which can be easily and satisfactorily made and installed, which in operation carries out the desired results and is not readily liable to get out of order.

In the drawings, Figure 1 is a vertical 40 sectional side view taken on the line 1 of Fig. 3. Fig. 2 is an inverted plan view of the entire device as it appears in Fig. 1. Fig. 3 is a plan view of the device removed from the wall or ceiling support.

In the preferred form of the device illustrated in the drawings it is suspended from a ceiling wall 10, but it may just as well be attached to a vertical side wall or an angular wall in a room without departing from this invention.

45 The ceiling 10 is provided with the usual projecting pipe end or fixture stud 12 having on its end screw threads 14 and one problem solved is to satisfactorily attach the bowl shaped hood 16 and shade holder 18 thereto so as to do away with the attachment of the fixture hood to the ceiling by

well known exposed attaching means such as screws through the rim into the ceiling. The fixture hood itself is provided with a central electric light socket device 22 held in place by a dome 24 of the character shown, described, and claimed in prior United States Patent, Number 962,055. In solving the above problem it is necessary to avoid interference with this or any other 60 similarly located lamp socket device and the electric wires 26 leading thereto and this result is accomplished by providing within the hood 16 an intermediate supporting member 27 which may be of any suitable 65 form so long as it bridges the lamp socket. This intermediate support has at its smaller end 28 screw threads adapted to engage the screw threads 14 of pipe or stud 12, here- 70 tofore described, and has at its larger end 75 an annular flange 30 having an opening 32 of greater diameter than the dome 24 so that the socket dome may, when the parts are brought together, pass entirely inside of the intermediate member 27, though normally 80 the member 27 is made of a less height than the interior height of the hood, as shown in the drawings.

Extending through the base of the shade holder 18, the central portion of the fixture 85 hood 16, and screw threaded into the flange 30 of the member 27 are a plurality of screws 34 adapted to be tightened up for the purpose of, as shown, rigidly securing the hood and the shade holder to the inter- 90 mediate member 27. These screws 34, are, as shown, of such a length that the member 27, shade holder and screws may be used with hoods of different heights and the screws 34 are, as shown, arranged around 95 the dome 24 of the hood so as to entirely clear it, as described, and the heads 36 of the screws are entirely concealed within the shade holder 18. It will also be seen that there being a plurality of such screws 34, 100 preferably only 2, the device rigidly clamps the hood 16 against the wall and as the strain is thus distributed on the various screws the danger of breaking the porcelain around any one of the screws is greatly 105 reduced.

When an electric lamp shade is attached to the shade holder 18 by the screws 38 of ordinary construction, provided for the purpose, and a lamp is placed inside the shade 110 and in the socket 22, said lamp is supported from the wall by the hood or dome 16 of

ornamental appearance held rigidly in place without any disfiguring visible securing devices.

It will be noticed that the screws 34 are long enough so that by loosening them the hood may be lowered sufficiently so that the wires 26 may be spliced. Cotter pins 40 are also provided so that the screws cannot be accidentally removed from the member 10 27 thus dropping the hood and shade holder and breaking them.

Having thus described my invention, what I claim as new and desire to secure by Letters Patent is:

15 1. In a device of the class described, the combination of a hollow fixture hood adapted to be secured to a wall, the same being provided with a central lamp socket, an intermediate supporting member inside the 20 hood straddling said socket device, means for securing the intermediate member to the wall, and means for securing the hood to said intermediate member located close to the socket so as to be practically concealed.

25 2. In a device of the class described, the combination of a hollow fixture hood to be secured to a wall provided at its center with an electric lamp socket, an intermediate member within the hood straddling said 30 lamp socket, a single connection between the intermediate member and the wall, and a plurality of connecting devices between the intermediate member and the hood arranged in proximity to but clear of the lamp 35 opening, for the purposes set forth.

3. In a device of the class described, in combination with a fixture hood to be attached to a wall and a shade holder to be attached thereto, a plurality of screws passing through the shade holder and hood in immediate proximity to a lamp socket in the hood and an intermediate connecting member between the hood and the wall engaged at one end by the said screws and 45 adapted at the other end to be detachably connected to a wall support.

4. In a device of the class described, in combination with a fixture hood to be attached to a wall and a shade holder to be attached thereto, a plurality of screws passing 50 through the shade holder and hood in immediate proximity to a lamp socket in the hood and an intermediate connecting member between the hood and the wall engaged at one end by the said screws and adapted 55 at the other end to be detachably connected to a wall support, said screws being of sufficient length to permit of substantial adjustment of the hood with reference to the support.

5. In a device of the class described, in combination with a wall having a fixture stud extending therefrom, a fixture hood adapted to cover said stud, an intermediate connecting member inside the hood screw 65 threaded upon said stud, and means detachably and adjustably connecting the hood to said intermediate member at a plurality of different points, said last mentioned means clearing but being in close proximity to the 70 lamp socket carried by the hood.

6. In a device of the class described, in combination with a wall and a fixture stud extending therefrom, a hollow hood covering said stud and provided on its outer central point with an electric light socket, a shade roller for said socket, screws passing through said shade holder and the hood, and an intermediate connecting member within the hood straddling the lamp socket thereof, entered and engaged by one end of said screws and at its other end screw threaded upon said fixture stud, the whole for the 75 purposes set forth.

In witness whereof, I have hereunto subscribed my name in the presence of two witnesses.

CHARLES G. RUSH.
